UNITED STATES PATENT OFFICE

121,131

DESIGN FOR AN INTERCOMMUNICATING TELEPHONE STATION CABINET OR SIMI- LAR ARTICLE

Adam Stolzenberger, Jr., Glendale, N. Y., as-
signor to Dictograph Products Company, Inc.,
New York, N. Y., a corporation of Delaware

Application March 29, 1940, Serial No. 91,338

Term of patent 7 years

To all whom it may concern:

Be it known that I, Adam Stolzenberger, Jr., a citizen of the United States, residing in Glendale, county of Queens, State of New York, have invented a new, original, and ornamental Design for Intercommunicating Telephone Station Cabinet or Similar Article, of which the following is a specification, reference being had to the accompanying drawing, forming a part thereof, in which:

Figure 1 is a front perspective view of the inter-

communicating telephone station cabinet or similar article showing the design; and

Fig. 2 is a side or end view thereof.

Opposite ends of the cabinet shown are identical and the rear wall thereof is a plain surface.

I claim:

The ornamental design for an intercommunicating telephone station cabinet or similar article, as shown and described.

ADAM STOLZENBERGER, JR.
